UNITED STATES PATENT OFFICE.

WILLIAM W. DEAN, OF ST. LOUIS, MISSOURI, ASSIGNOR TO THE BELL
TELEPHONE COMPANY OF MISSOURI, OF SAME PLACE.

TELEPHONE-EXCHANGE SYSTEM.

SPECIFICATION forming part of Letters Patent No. 597,053, dated January 11, 1898.

Application filed September 22, 1897. Serial No. 652,538. (No model.)

To all whom it may concern:

Be it known that I, WILLIAM W. DEAN, a citizen of the United States, residing at St. Louis, in the State of Missouri, have invented 5 a certain new and useful Improvement in Telephone-Exchange Systems, (Case No. 28,) of which the following is a full, clear, concise, and exact description, reference being had to the accompanying drawing, forming a part of 10 this specification.

My invention relates to telephone-exchange systems in which trunk-lines are employed for connecting switchboards at the same or different exchanges, wherebysubscribers connected 15 at one board may communicate with subscribers connected at other boards.

My invention has for its object the adaptation of trunk-line systems for use in connection with automatic means jointly controlled 20 by the subscribers and operators for including calling-generators in circuit with and disconnecting the same from the bells at the called-subscribers' stations.

Telephone-exchange systems employing 25 the automatic means referred to form subject-matter of my applications for United States Letters Patent. For example, in my application filed August 2, 1897, Serial No. 646,832, is shown a telephone system equipped 30 with one of the automatic ringing devices referred to. In systems such as is shown in my aforesaid application the calling-generator is automatically thrown into circuit with the called-subscriber's bell when the connecting-plug completes the connection between the calling and called subscribers. The 35 called subscriber in responding to the signal thus automatically conveyed upon removing his telephone from its hook operates the automatic apparatus at the central office to remove 40 the generator from line. I have found that for various reasons it is undesirable when the called subscriber is connected at another board to ring his bell automatically 45 through the agency of the cord-connecting apparatus and automatic ringing means at the calling-subscriber's board. Signaling from the calling-subscriber's board is especially objectionable when the trunk-lines extend 50 for many miles between different exchanges.

If it were not for my present invention it would be better practice to employ special cord-connecting apparatus at each exchange or board for use in connecting the subscribers for conversation through trunk-lines, the special cord-connecting apparatus being unprovided with the automatic ringing apparatus to obviate the various difficulties that would otherwise arise in the different trunk-line telephone systems.

By means of my present invention I am enabled to employ cord-connecting apparatus of a uniform type at the various exchanges or boards, which, while it is adapted for automatic signaling when used to connect subscribers at the same board, is, through the agency of my invention, equally adapted for connecting subscribers at distant boards or exchanges by means of trunk-lines.

My invention consists, generally speaking, in providing means associated with each trunk-line adapted to operate the automatic ringing apparatus to remove the generator from circuit with the trunk-line when the trunk-line is connected with the cord-circuit.

I will explain the preferred embodiment of my invention and one application thereof by reference to the accompanying drawing, which illustrates two subscribers' stations, each connected with separated exchanges or boards by telephone-lines and a trunk-line extending between said boards.

The apparatus illustrated will be readily understood by those skilled in the art, and I do not therefore deem a detailed description thereof to be essential.

The subscriber A is connected with a telephone-exchange B, being connected in multiple therat with spring-jacks located at 90 boards $a a' a''$. The line-indicating apparatus a^3 is operated upon the removal of the telephone-receiver at station A in a manner well understood by those skilled in the art. The subscriber C is one of a number connected 95 with board D, which may be at the same exchange with the boards $a a' a''$ or at a distant exchange. The line of subscriber C terminates in a spring-jack b . The line-indicator c , corresponding to subscriber C, may be 100 operated by rotating the armature of the grounded generator c' normally included in

circuit with the signal-bell c^3 , gravity-hook c^4 , limb c^4 , and the long line-spring of the spring-jack, which is normally in circuit with the line-indicator.

5 I have illustrated an answering-plug d and a connecting-plug e , which are united through a centralized battery f and repeating coils $f' f'$ in a manner well known. Each plug is provided with a tip and sleeve adapted to make contact with the short and long line-springs of each spring-jack, respectively, the tips being telephonically united by a strand g , while the sleeves are likewise united by a strand g' .

10 15 The operation of the clearing-out indicators h and h' and the apparatus forming the same forms no part of my present invention, and as the operation thereof will be readily understood by those skilled in the art I do not deem a further reference thereto to be essential.

20 A telephone-key l is provided to include the operator's telephone apparatus in a bridge of the cord-circuit. A trunk-line extends in two limbs $i i'$ from the board D to the boards $a a' a^2$ in multiple. A retardation-coil k , which will pass currents of low frequency formed by the calling-generator and which is adapted to obstruct voice-currents, is preferably included in a bridge of the trunk-line. In an outgoing trunk-line the retardation-coil is preferably located at the exchange from which the trunk-line extends. At the board D, I have illustrated an operator's telephone-key l' , which is adapted to bridge the operator's telephone set l^2 between the limbs of the telephone-line, which terminate in a sleeve and tip of the trunk-line connecting-plug m . The tip and sleeve of the plug are adapted to make contact with the short and long line-springs of spring-jack b .

25 30 35 40 45 I have illustrated a ringing-key n , which upon the insertion of the plug m is adapted, when actuated, to direct calling-current from the generator n' through the signal-bell c^2 . An operator's indicator o is included in a grounded conductor o' , extending from the thimbles of the trunk-line jacks at the exchange B.

50 55 The details of the particular automatic ringing apparatus that I have here shown are fully explained in my aforesaid application, and I will only refer to the parts and their functions in the following description of the operation of the system.

Subscriber A, desiring communication with subscriber C, removes his telephone from its hook and thereby lights the lamp of indicator a^3 . The operator at the board where the indicator a^3 is located inserts the answering-plug d within the spring-jack of the calling subscriber at her board, and having ascertained that C is the desired subscriber the operator then inserts the connecting-plug e in the trunk-line jack at her board. By this act the grounded battery p is closed through the operator's annunciator o at board D. The

generator having been removed, as will be hereinafter explained, the D operator listens in and ascertains that connection with subscriber C is desired, thereupon signaling said subscriber by operating her ringing-key. As in the system of my aforesaid application the armature of magnet q is attracted when the plug e is inserted in the trunk-line jack, since circuit is completed through the same from the grounded battery p to the grounded terminal of annunciator o , the calling-generator r of ringing-current being thus connected through magnet s with limb i of the trunk-line. Now in the particular trunk-line system here shown in order that the operators may converse it is essential that the ringing-current generator be disconnected from the telephonic circuit. To accomplish this, I preferably include the retardation-coil k in a bridge of the trunk-line, said retardation-coil, as stated heretofore, being capable of passing currents of low frequency from the calling-generator while it obstructs the voice-currents. As soon as the connecting-plug e is inserted within the trunk-line jack a path of low resistance is provided for the generator-current through the coil k . This path may be traced from the grounded generator through magnet s , sleeve of plug e , the long spring of the spring-jack engaging the plug, the retardation-coil k , the short line-spring of said jack, the tip of the inserted plug, a portion of strand g to the grounded connection g^2 . The magnet s is thus energized sufficiently to attract its armature, which thereupon withdraws the stop carried thereupon from the path of the spring or ringing-switch t , which by its own resiliency breaks contact with the generator contact-anvil r' , the generator thus being completely removed from its connection with the trunk-line.

50 55 60 65 70 75 80 85 90 95 100 105 110 115 The grounded bell at each of the subscribers' stations connected with the exchange B is of high resistance, so that when subscribers are connected for conversation at said exchange the generator will be automatically included in circuit with the bell, and upon the removal of the called-subscriber's receiving-telephone from its hook this high-resistance path will be replaced by a low-resistance path, which will cause a sufficient increase of the generator-current to operate the magnets.

120 125 I have herein shown but one type of trunk-line; but it will be obvious to those skilled in the art that my invention may be employed to advantage in connection with other types of trunk-lines.

130 135 While I have shown one particular form of automatically-controlled signaling apparatus at one of the exchanges, other types may be employed to perform the same work. I do not therefore wish to be limited to the precise apparatus herein shown and described; but.

Having thus described my invention, I claim as new, and desire to secure by Letters Patent, only with the limitations expressed or by law implied, the following:

1. In a trunk-line telephone system, the combination with two switchboards, of a plurality of subscribers connected with each of said boards, signal-receivers at the subscribers' stations, a trunk-line extending between the boards, switching apparatus at one of said boards for uniting subscribers for conversation, a calling-generator, means for including the same in circuit with the signal-receiver at a called-subscriber's station connected with the latter board, electromagnetic means for removing said generator, apparatus at the subscribers' stations connected with the latter board, each being adapted when its station is the called station to operate the latter, means to remove the calling-generator from circuit with the signal-bell, and a conductor normally connected with the trunk-line adapted to alter the operative condition of the electromagnetic means and to be connected therewith by the switching apparatus upon the manipulation thereof to connect a subscriber whose telephone-line extends to the latter board with the trunk-line extending to the other board, whereby the generator is disconnected immediately upon the establishment of connection with the trunk-line, substantially as described.

2. In a trunk-line telephone system, the combination with two switchboards, of a plurality of subscribers connected with each of said boards, signal-receivers at the subscribers' stations, a trunk-line extending between the boards, switching apparatus at one of said boards for uniting subscribers for conversation, a calling-generator, means for including the same in circuit with the signal-receiver at a called-subscriber's station connected with the latter board, an electromagnetic circuit-changing device adapted to remove said generator from circuit with the called-subscriber's bell, switches at the subscribers' stations connected with the latter board, each switch being adapted when its station is the called station to operate said electromagnetic circuit-changing device to remove the calling-generator from circuit with the bell, and a conductor adapted to change the operative condition of the electromagnetic circuit-changing device, said switching apparatus being adapted to connect said conductor with and disconnect it from said electromagnetic circuit-changing device when manipulated to connect a subscriber at the latter board with the trunk-line and to disconnect said subscriber from said trunk-line, substantially as described.

3. In a trunk-line telephone system, the combination with two boards, of a plurality of subscribers connected with each board, cord-connecting apparatus at one of said boards for uniting subscribers for conversation, a calling-generator, an electromagnet jointly controlled by the cord-connecting apparatus and the apparatus at each subscriber's station connected with the latter board when its station is the called station for in-

cluding the generator in circuit with and removing it from the signal bell or receiver at the called-subscriber's station, a trunk-line 70 between the boards, a terminal switch or jack of the trunk-line adapted for connection with the cord-connecting apparatus, and means jointly controlled by the cord-connecting apparatus and said terminal switch 75 adapted to effect the removal of the generator from circuit upon the connection of the terminal switch and cord-circuit, substantially as described.

4. In a trunk-line telephone system, the combination with two switchboards, of a plurality of subscribers connected with each board, cord-connecting apparatus for uniting subscribers for conversation at one of said boards, signal receivers or bells at each subscriber's station of comparatively high resistance, a calling-generator, means at the latter board for connecting said generator in circuit with the signal-bell of a called subscriber, an electromagnet included in the circuit traversed by the calling-current, switches, one at each of the subscribers' stations connected at the latter board, each switch being adapted when its station is the called station to furnish a path of low resistance for the generator-current, said electromagnet being adapted when the current is thus increased to remove the generator from circuit with the called-subscriber's signal-bell, and a retardation-coil connected with said trunk-line affording a 100 path of low resistance for the signaling-current upon the connection of said trunk-line with the cord-connecting apparatus, whereby the generator is removed from circuit immediately upon the connection of a cord-connecting apparatus with the trunk-line, said retardation-coil being wound to permit of the passage of the calling-current and to obstruct the high-frequency voice-currents, substantially as described.

5. In a trunk-line telephone system, the combination with two switchboards, of a plurality of subscribers connected with each board, cord-connecting apparatus for uniting subscribers for conversation at one of said boards, signal-receivers at each subscriber's station, a calling-generator, a ringing-switch adapted when the cord-connecting apparatus is manipulated to connect subscribers at the latter board for conversation to direct current 115 from said generator to the signal-receiver at the called-subscriber's station, the circuit traversed by said calling-current being of high resistance, an electromagnet connected in said circuit, switches, one at each of the subscribers' stations connected at the latter board, each switch being adapted when its station is the called station to furnish a path of low resistance for the generator-current, said electromagnet being adapted when the 120 current is thus increased to remove the generator from circuit with the called-subscriber's signal-receiver, and a path of low resistance which is completed through said genera-

tor and electromagnet when the cord-connecting apparatus is united with the trunk-line whereby the generator is removed from the trunk-line, substantially as described.

- 5 6. In a trunk-line telephone system, the combination with two switchboards, of a plurality of subscribers connected with each of said boards, signal-receivers at the subscribers' stations, a trunk-line extending between the boards, switching apparatus at one of said boards for uniting subscribers for conversation, a calling-generator, means for including the same in circuit with the signal-receiver at a called-subscriber's station connected with the latter board, means for removing said generator, apparatus at the subscribers' stations

connected with the latter board, each being adapted when its station is the called station to operate the latter, means to remove the calling-generator from circuit with the signal-bell, a switch or jack for the trunk-line, and means jointly controlled by the switching apparatus and the latter switch adapted to effect the removal of the generator from circuit, substantially as described. 25

In witness whereof I hereunto subscribe my name this 17th day of September, A. D. 1897.

WILLIAM W. DEAN.
